UNITED STATES PATENT OFFICE.

KNOWLES S. CHARLWOOD, OF BALDWYN, MISSISSIPPI.

RAILROAD TIE.

Application filed August 11, 1926. Serial No. 123,642.

This invention relates to a railway tie. The primary object of this invention is the provision, in a manner as hereinafter set forth, of a railway tie adapted to receive a wooden rail chair in such manner as to provide for the ready removal and replacement of the chair when the same has become worn, broken or rotted, without damage to the body of the tie and further where-
10 by a tie body reinforcing element is employed to prevent lateral displacement of the chair.

The invention contemplates the provision of a tie constructed of steel, concrete or other appropriate material, having adjacent each end thereof a dove-tailed recess in the center of the bottom of which recess a bore or pocket is formed. Adapted to be placed in each of these recesses of a tie, is a correspondingly shaped rail chair of wood through which a tie body reinforcing rod is passed to prevent lateral shifting of the chair. A rail is then placed upon the chair, and securing spikes are then driven into the chair upon either side of the rail, in the usual manner. It will be readily understood that the chairs cannot be moved laterally due to the engagement of the reinforcing rod therewith. Removal and replacement
25 of the chair is accomplished by withdrawing the rod and spikes whereupon the chair can be readily removed and a new one placed into position without moving rail or tie.

The invention will be best understood from a consideration of the following detailed description taken in connection with the accompanying drawing forming a part of this specification, with the understanding, however, that the invention is not confined
35 to any strict conformity with the showing of the drawing but may be changed or modified so long as such changes or modifications mark no material departure from the salient features of the invention as expressed in the appended claims.

In the drawings:—

Figure 1 shows the tie embodying this invention, in top plan.

Figure 2 is a central longitudinal section of the tie, the section being taken upon the line 2—2 of Figure 1.

Figure 3 is a section on line 3—3 of Figure 2.

Referring now to the drawing in detail wherein like numerals of reference indicate corresponding parts throughout the several

views, the tie body is indicated by the numeral 1. This body may be formed of concrete or steel as desired, and which has embedded therein a set of tubular members positioned in lengthwise alinement and in spaced relation. The tubular members of said set are indicated at 2, 3 and 4. Arranged below the members 2, 3 and 4 and embedded in the tie body 1 is a tubular mem- 65
ber 5.

Extending longitudinally through the tie body is a pair of reinforcing rods 6, 7. The rod 6 extends through the set of tubular members and the rod 8 through the member 5. The rods 6, 7, project from the ends of the tie body 1 and are provided with securing nuts 8. It will be readily understood that in the event of the fracture of the tie, if it is formed of cement, the nuts 8 can be 75 tightened up upon the rods and the tie thus held together until such time as proper replacement thereof can be made.

Formed in one face of the tie body adjacent each end thereof, is a substantially 80 dove-tailed recess 9.

Fitted into each of the dove-tailed recesses 9 is a correspondingly shaped wood block 10 which constitutes a rail chair. These wood blocks each have a groove 11 85 at the transverse median line of the lower face thereof. When the blocks 10 are placed in position, they are inserted into the recesses 9 from one side of the tie body 1 and it will be readily understood from the showing in the drawing that the inclined side surfaces of the blocks and walls of the recesses will engage to prevent the removal of the blocks by lifting the same upwardly. When the blocks are in the position shown, 95 the grooves 11 receive the rod 6 which will prevent the removal of the blocks by an attempt to slide the same to the right or left, or in other words will prevent lateral displacement of the chair.

With a tie thus constructed and having the blocks in position in the manner described, the tie after being placed in location, is ready to receive the rails thereover. The rails, indicated by the numerals 105 12 are laid transversely of the tie in the usual manner, across the central portion of the blocks 10. Securing spikes 13 are then driven into the blocks 10 to secure the rails to the blocks, in the same way in which rails are ordinarily secured to wood ties.

Formed in the upper face of the tie 1, are

a plurality of recesses 14 in which a pick or other tool may be engaged to draw the tie into position.

The tubular members 2, 4 have their inner ends flush with the outer walls of the recesses 9, and the tubular member 3 has its ends flush with the inner walls of the recesses 9. The rod 6 extends transversely of both recesses.

10 From the foregoing description it will be readily understood that a rail cushion of approved material can readily be employed in connection with concrete or steel ties and when such cushions become worn, split or 15 rotten, they can be easily and quickly replaced without damage to the body of the tie.

Having thus described my invention what I claim is:—

20 1. A railway tie of the character described, comprising an elongated body having a transversely extending dovetail recess adjacent each end thereof, a rail supporting cushion block of dovetail shape mounted in each of said recesses, a reinforcing rod em- 25

bedded in said body and extending through said blocks to prevent lateral displacement thereof, and spaced tubular members enveloping said rods, said members flush with the walls of said recesses.

2. A railway tie of the character described, comprising an elongated body having a transversely extending dovetail recess adjacent each end thereof, a rail supporting cushion block of dovetail shape mounted in each of said recesses, a reinforcing rod embedded in said body and extending through said blocks to prevent lateral displacement thereof, and spaced tubular members enveloping said rods, said members flush with the 30 walls of said recesses, said blocks having grooves in the lower faces thereof for the passage of said rod, a lower reinforcing rod embedded in said body, and a tubular member of the same length as the length of the 35 tie body and enveloping said lower rod.

In testimony whereof, I affix my signature hereto.

KNOWLES S. CHARLWOOD.
